UNITED STATES PATENT OFFICE

WALTER S. HULSE, OF MERCHANTVILLE, NEW JERSEY

COMPRESSED AIR OPERATED PUMP

Application filed November 15, 1930. Serial No. 495,973.

This invention relates to compressed air operated water pumps and particularly to certain improvements in compressed air operated pumps of the character illustrated and described in my Patent 1,472,839 granted on November 6, 1923. In this patent, I illustrated a pumping mechanism including a pump cylinder adapted to be submerged and having a shiftable valve shiftable by differences of pressure upon opposite sides of the valve when the cylinder is full and when it is approximately empty, the valve controlling the admission of pressure fluid to the cylinder for forcing the water therefrom when the cylinder is full and controlling the release of pressure fluid from the interior of the cylinder when the water has been discharged from the cylinder to the desired amount.

One of the objects of the present invention is to provide means whereby the mechanism controlling the inlet of air to and the outlet of air from the cylinder may be separated from the pump cylinder itself so that a remote control is provided and so that the controlling parts may be placed in a position where they are readily accessible for repair, lubrication or the like.

A further object is to provide a modified form of balance tube of the character shown in my prior patent and to provide positive means for opening the valve permitting the inlet of compressed air to the cylinder and closing the air exhaust valve, said positive means operating in connection with the balance tube.

A further object is to provide means whereby air in the balance tube gradually lost by absorption in the water may be replaced or replenished.

A further object is to provide means whereby a weight and lever will act to positively operate the valves controlling the exhaust of air from the pump cylinder and the inlet of compressed air thereto and to provide in connection with this lever, means whereby the lever will be caused to quickly move from one of its positions to the other to cause a quick action of the valves.

Other objects will appear in the course of the following description.

My invention is illustrated in the accompanying drawings, wherein:—

Figure 1 is a diagrammatic elevation partly in section of a pumping apparatus constructed in accordance with my invention;

Figure 2 is a like view to Figure 1, but showing a slightly different form of apparatus;

Figure 3 is an enlarged longitudinal sectional view of the lever for operating the valves;

Figure 4 is a diagrammatic view of the lever showing the forces applied thereto.

Referring to Figure 1, 10 designates the pump cylinder which is submerged in the water of the well W. The lower end of this pump cylinder is provided with an inlet valve 11 which opens inwardly. This may be of any suitable character but is shown as a flap valve. Extending upward through the cylinder 10 and out through the top of the cylinder is a discharge pipe 12 having therein, above the top of the cylinder 10, the check valve 13. This pipe 12 extends nearly to the bottom of the cylinder 10. The check valve 13 may be located anywhere along the water discharge pipe 12.

Disposed remote from the cylinder 10 and at the surface of the ground is a chamber 14 having therein either a piston 15 or a diaphragm, the piston and diaphragm being considered as equivalent elements. This element 15 will be hereafter referred to as the piston, though the term is to be understood as including the diaphragm. The piston 15 is connected to a piston rod 16 passing through opposite ends of the cylinder 14. Extending upward from the top of the cylinder 10 is a pipe 17 which is connected to two branches, one an air supply branch 18 connected to a source of compressed air, and the other branch being an air discharge pipe 19. In the branch 18 or air supply pipe there is disposed a valve 20 and in the air discharge pipe 19 there is disposed a valve 21. When one of these valves is closed, the other is opened and vice versa. These valves 20 and 21 may be of any suitable

character and are merely shown diagrammatically in the drawings.

Engaged with the lower end of the rod 16 is one arm of a lever 22, the other arm of which carries a weight 23 tending to force the short arm of the lever up and thus opening the valve 21 and closing the valve 20.

The particular construction of the lever 22 will be hereafter stated.

Extending from the top of the cylinder 10 is the pipe 24 which opens into the chamber 14 below the piston 15. Extending from the upper end of the chamber 14 above the piston 15 is a pipe 25 which I shall hereafter call the balance pipe which extends downward through the top of the cylinder 10 and extends down nearly to the lower end of the water discharge outlet 12 and is there provided with a bell 26 open at its lower end. Preferably, and for the purpose of supplying air to the pipe 25 in order to compensate for the absorption of air by the water within the lower end of this pipe, there is provided an air supply pipe 27 which is connected to the air supply pipe 18 beyond the valve 20 and to the pipe 25 beyond its point of connection to the chamber 14. Disposed in this pipe 27 is a needle valve 28 permitting of a small leakage of air from the air supply pipe into the pipe 27 and so into the pipe 25. A manually operable valve capable of being turned on and off might be used in place of the needle valve.

The lever 22 is preferably hollow and contains therein a volume of mercury or like material designated 29. The lever is tubular so that the mercury can run from one end of the lever to the other. When that arm of the lever which is engaged by the rod 16 is depressed, the mercury will run to that end of the arm to partially counter-balance the weight 23. When on the other hand, the lever has shifted even slightly, from its horizontal position, the mercury will run to the extremity of the weighted end of the arm, thus assisting the weight 23. This mercury, it will be understood, also tends to cause the quick movement of the lever from its two positions. Preferably the weight 23 is shiftable along the arm any desired distance from the fulcrum 22^a of the lever.

The operation of the construction illustrated in Figure 1 is as follows:

It is assumed that the cylinder 10 is submerged in water and that the cylinder is practically empty. In this position of the parts, the weight 23 will have lifted the piston 15 opening the valve 21 and closing the valve 20, cutting off the compressed air supply and permitting the discharge of air from within the cylinder 10. The water will now enter the pump cylinder through the check valve 11 and the air above the water will escape through the pipe 17, the connection 19 and the valve 21. As the water rises above the

bell 26, air in 26 will be compressed, the pressure being communicated through the pipe 25 to the upper side of the piston 15. When the water has risen to a predetermined extent, this pressure will force the piston down against the action of the counter-weight 23, closing the valve 21 and opening the valve 20. Compressed air will now enter the cylinder through the pipe 17, forcing the water out through the discharge line 12. Under these circumstances, additional pressure will be put on the air in the bell 26 and the pipe 25, but the volume of the bell 26 is sufficiently large in proportion to the volume of the pipe 25 that the reduction of volume of the air in these parts does not cause the water to rise to a greater extent than some fraction of the height of the bell 26. As the water level in the cylinder 10 recedes, the pressure on the opposite sides of the piston 15 will tend to equalize and as soon as the pressures on opposite sides have nearly equalized, the lever 22 with its weight 23 will again lift the piston and again shift the valves.

This operation takes place alternately and continuously. In my prior patent, the water column in the balance tube was alternately lower and higher than the water in the cylinder 10. In the present invention, however, as shown in Figure 1, the water level remains near the lower end of the balance tube and the pressure through the balance tube is greater than that from the top of the cylinder 10, the difference acting against the lever 22 and its weight 23.

As the air in the pipe 25 and bell 26 will gradually be lost by absorption in the water, I have provided the connection 27, as a means for replacing the air that is lost. The needle valve 28 (if one is used) may be set to permit a continuous slight leakage of air or it may be opened occasionally, if a manually operable valve is used, as the operator may choose, in order to replace or replenish the air within the bell 26 and pipe 25.

In Figure 2, I have shown an arrangement which may be used where there is a relatively short distance between the air valves and the pump and where the action of the pump is slow enough so that high velocities in the air lines are not required. In this figure, like numerals are used for like parts. In this figure, the cylinder 10 is shown longer than the cylinder 10 in Figure 1, and is provided at its lower end with a flap valve 11 as heretofore described and with the outlet water discharge pipe 12 having therein the check valve 13. Associated with the cylinder 10 is the piston chamber 14 having therein a piston 15 as heretofore described. This piston carries the piston rod 16 bearing against the one arm of a lever 22 fulcrumed at 22^a and having the counter-weight 23 and a portion of liquid such as mercury 29.

In this case, I do away with the use of the

pipe 17. The pipe 24 extending upward from the top of the cylinder 10 is the air exhaust pipe controlled by the valve 21. The balance pipe 25 is connected directly to the valve 20 and extends downward through the top of the cylinder 10 and has a relatively long bell 26^a corresponding except in length with the bell 26. The pipe 24 is connected by a branch 24^a to the lower end of the chamber 14 while the air supply pipe 25 is connected by a branch 25^a to the upper end of the chamber 14. A needle valve 30 is disposed at the end of the air exhaust pipe 24 beyond the valve 21 and a needle valve 31 is disposed at the inlet end of the air supply 25 beyond the valve 20.

The valves 30 and 31 may be needle valves or not as circumstances may dictate. These valves are placed at the exhaust and supply lines to regulate the flow of air so that there will be no changes of pressures on the piston so abrupt as to interfere with the operation of the mechanism.

The general action of the pump is the same as for the pump shown in Figure 1. The lever 22 with its weight opens the exhaust valve 21 and closes the air supply valve 20. As the air in the cylinder 10 escapes through the pipe 24, water enters through the flap valve 11 and rising above the mouth of the bell 26^a compresses the air in 26^a and in the pipe 25. This pressure is communicated to the upper side of the piston 15, forcing the piston down against the action of the counter-weight 23, closing the valve 21 and opening the valve 20. Compressed air will now enter through valve 20 and pipe 25, rising through the water from the bottom of the bell 26^a to the top of the cylinder where it builds up a pressure that forces water out through the discharge pipe 12.

As the water recedes, the pressures on opposite sides of the piston 15 tend to equalize and then the lever and weight can operate the valves.

The lever 22 is preferably of iron, (if mercury is to be used), and inasmuch as the hollow interior of the lever 22 is partially filled with mercury, the mercury will run from one end to the other with the movement of the lever. This mercury at first resists a movement of the lever and then when the lever is moved beyond a horizontal position in either direction, gives an impulse to the movement of the lever and piston. This assures that a movement once started will be completed, prevents a state of equilibrium in the action of the piston, and furthermore gives the piston lever a quick final action. Of course, it will be understood that any liquid may be pumped by this mechanism, whether water, oils, acids, or the like and where I have used the word "water" it is intended it shall cover any liquid. Likewise the word "air" as used in this specification is

intended to cover any other gas such as natural gas, air-inert gas, etc.

It will be seen that there are two pressures acting on opposite sides of the piston 15, one of these pressures, which is the pressure on top of the liquid in cylinder 10 is transmitted to the lower side of the piston by the equalizer pipe 24 and its branch 24^a. The other pressure, which is the pressure on top of the liquid in the pump cylinder 10, plus the pressure due to the height of the water in the pump cylinder above the bottom of the balance pipe 25 and its bell 26, is transmitted to the upper side of the piston by the balance pipe 52. The difference in these pressures, that is, the pressure acting on the under side of the piston and that acting on the upper side is due to the height of water in the pump cylinder above the bottom of the balance pipe or above the bottom of the bell 26, whether this pressure on top of the water is atmospheric or a higher pressure as the pressure on top of the water is balanced out by the equalizer pipe.

As this force or pressure P in the pipe 25 varies with the height of water in the pump cylinder, it is necessary to so design the lever 22 and its weights 23 and 29 that when the pressure above the piston has reached a corresponding value to the height to which we wish the pump cylinder to be filled, it will overbalance the weights 29 and 23 to cause the valves to operate. The moments due to the weights on the lever must now be changed so that the lever will not overbalance the pressure or force exerted on the top of the piston as this force decreases with the fall of the water level in the pump cylinder until the water has fallen a desired amount. This is accomplished by using the movable weight, as for instance, the weight of the mercury 29, which as soon as the weighted end of the lever has been raised to a point where the lever is slightly beyond the horizontal, flows to the opposite end of the lever. The length of the lever arms and the value of the fixed and movable weights should be so proportioned to one another as to give the required moments of rotation around the fulcrum. The maximum head against which the pump is to operate has no bearing on the design except in determining the size of the bell at the lower end of the balance tube.

In Figure 4, it is shown that the piston rod 16 impinges on the lever 22 only a short distance, as for instance one inch from the fulcrum. This is desirable because the stroke of the piston should be very short and the slope of the lever should be rather steep. The short stroke of the piston operating at a considerable distance from the fulcrum would not give the required slope to the lever, this slope being required in order that the mercury may move rapidly from one end of the lever to the other.

One of the particular features of this pump is the use of the balance tube and the tube 25 connecting therewith and communicating with the cylinder of the valve operating mechanism on one side of the piston (or diaphragm) and the tube 24 connecting with the upper portion of the pump cylinder and communicating with the cylinder of the valve operating mechanism on the opposite side of the piston, by which arrangement of tubes, a difference in pressure, which is directly proportional to the height of water in the pump cylinder, is caused to act on the piston of the valve operating mechanism.

Another feature of the invention is in the use of the fixed weight 23 and the movable weight with the several parts so arranged that the pressure in the balance tube 25 and the upper portion of the pump cylinder being communicated to the opposite sides of the piston, the differences between these pressures will create a force tending to move the piston in one direction, which will be opposed by the action of the lever and weights tending to move the piston in the opposite direction, the movable weight, by being transferred from one end of the lever to the other with movements of the lever, giving two definite values to the force exerted by the lever and fixing definite heights of water in the pump cylinder for which the difference in the pressures on the piston and the opposing action of the lever will cause the piston to move in one direction or the other, thus causing the simultaneous opening of one valve and the closing of the other valve in proper order for the operation of the pump.

The advantages claimed for this pump in addition to those common to all pumps of this general class, are that the shifting of the air inlet and exhaust valves is positively controlled by the level of the liquid in the pump cylinder to the same extent as in pumps in which the operation of these valves is controlled by a float or floats in the pump cylinder with the elimination of the floats, rods, levers and packing sleeves that are required with floats and with generally less clearance in the pump cylinder than is possible where floats are used. Another advantage lies in the elimination of all moving parts in the pump cylinder itself with the exception of the two check valves, one of which is in the pump cylinder proper and the other of which is in the discharge pipe 12. This permits the pump cylinder or tank to be built in a variety of shapes from a tank of very small diameter to be used in a driven well to a tank of large lateral dimensions to be used in a shallow sump, proper proportioning of the balance tube and piston of the valve operating mechanism causing the pump to operate with any particular rise and fall of the water in the pump cylinder desired, from

one of only a few inches to one of several feet.

Another advantage due to my construction is that the valve operating mechanism can be placed at a considerable distance from the pump cylinder securing a remote control and permitting it to be placed in an accessible location where the pump cylinder itself is in an inaccessible location as for instance when placed in a well.

Another advantage due to my construction is that the positive control of the air valves is negligibly affected by variations in the depth to which the pump cylinder is submerged or to variations in the head against which it is pumping. Furthermore, the positive control of the shifting of the air valves assures that the discharge stroke will not begin until the pump cylinder is completely filled with liquid and that the discharge stroke will end before air can pass through the pump and out through the water discharge pipe, thus making this pump especially desirable for pumping the maximum capacity of a low yield water or oil well, or for use as a sump pump as no energy is wasted, or consumed except when the pump is actually pumping.

In order to further explain the function of the lever 22 with its permanent weight 23 and movable weight 29, in regulating the stroke and point of cut-off of the pump, attention is directed to the diagram in Figure 4.

Assume that the weight of piston and the piston rod is two pounds and the pressure P acting on the upper face of the piston is 26.5 pounds when the water is at a level X—X. The total force acting on the piston will then be $28\frac{1}{2}$ lbs. Assume that the fixed or permanent weight 23 is 1 lb. and the weight of the mercury 29 one lb. It is obvious that the length of the arm d must be 14.25" as shown by the following equation:

$$28.5 \text{ lbs.} \times 1 = 2 \text{ lbs.} \times 14.25"$$

This will bring the lever 22 to a horizontal position and at this time the mercury will flow to the other end of the lever, thus holding the lever with the weight raised. The weighted end of the lever must remain raised until the water in cylinder 10 has discharged. If it were not for the mercury 29 or other shiftable weight, the permanently weighted end of the lever would lower just as soon as the pressure in the balance pipe 25 has decreased by the lowering of the water slightly below the point X—X, but as the mercury has shifted over to the opposite end of the lever from the permanent weight, it acts to counter-balance the weight until the water has been lowered to slightly below Y—Y, the points X—X and Y—Y being the levels of water in the pump at which the forces on

the lever are in equilibrium with the mercury at opposite ends of the lever.

When this happens, for instance, when the pressure above the piston has been reduced to five pounds, the weight 23 is sufficient to counter-balance the movable weight 29, the lever tilts down on its permanently weighted end, and the mercury again flows to the permanently weighted end of the lever. Under these circumstances, the arm d of the lever must have a certain relation to the arm d' based upon the following equation:

$$1 \text{ lb.} \times 14.25'' = 7 \text{ lbs.} \times 1 \text{ in.} + 1 \text{ lb.} \times d'' \text{ or } 7.25.$$

16 In this equation, the weight of the lever, that is, the relative weights of the two arms of the lever have been disregarded, and as d has a length twice as long as the arm d' the fixed weight will have to be reduced to compensate for the excess weight of the lever arm d . Of course, the fixed weight 23 could be eliminated and the arm d be extended to form or constitute said fixed weight. It will, therefore, be seen that the movable weight not only constitutes a means whereby the action is rapid in shifting the piston but that it is a very important feature of the invention inasmuch as it prevents any movement of the piston when the water is being discharged until the water has lowered to a definite point and prevents any movement of the piston when the water is entering the cylinder and until the water has risen to a definite point.

35 I claim:

1. In a pump of the character described, a tank having an inwardly opening check valve, a discharge pipe extending from the bottom of the tank, a pipe leading from a source of compressed fluid into the tank and having a valve, and an exhaust pipe leading from the tank and having a valve, means positively acting to urge the air supply valve to a closed position and the exhaust valve to an open position, and fluid pressure operated means acting against the force of said urging means, when the tank is filled to a predetermined degree, to shift the air supply valve to an open position and the exhaust valve to a closed position against the action of said urging means, the means urging the air supply valve to a closed position and the exhaust valve to an open position acting automatically when the liquid has fallen in the tanks to such a degree that the pressure of air is less than the force exerted by said urging means to open the air exhaust valve and close said air supply valve, the shifting of said valves resulting solely from changes in the magnitude of the force exerted by said fluid pressure operated means caused by the rise and fall of the liquid level in said tank.

2. In a pump of the character described, a tank having an inwardly opening check

valve, a discharge pipe extending from bottom of the tank, a supply pipe leading from a source of compressed fluid into the tank and having a valve, an exhaust pipe leading from the tank and having a valve, a chamber having a piston operating therein and having a positive connection to the two valves, the piston when moved in one direction acting to close the supply valve, and open the exhaust valve, and when shifted in the other direction simultaneously opening the supply valve and closing the exhaust valve, regulatable means positively urging the piston in a direction to open the discharge valve and close the supply valve, and means acting when the tank is full to shift the piston to open the supply valve and close the exhaust valve against the action of said urging means and including a tube connected at that end of said chamber opposed to the urging means, said tube extending downward into the tank and terminating at a point above the discharge pipe, and an equalizing pipe connected to the opposite end of said chamber and extending into the tank.

3. In a pump of the character described, a tank having an inwardly opening check valve, a discharge pipe extending from bottom of the tank, a supply pipe leading from a source of compressed fluid into the tank and having a valve, an exhaust pipe leading from the tank and having a valve, a chamber having a piston operating therein and having a positive connection to the two valves, the piston when moved in one direction acting to close the supply valve, and open the exhaust valve and when shifted in the other direction simultaneously opening the supply valve and closing the exhaust valve, regulatable means positively urging the piston in a direction to open the discharge valve and close the supply valve, and means acting when the tank is full to shift the piston to open the supply valve and close the exhaust valve against the action of said urging means and including a tube connected to that end of said chamber opposite the urging means, said tube extending downward into the tank and terminating in a downwardly opening bell larger in diameter than the tube, there being means for nearly equalizing the fluid pressure on opposite sides of the piston when the liquid in the tank has descended to a predetermined degree to thereby permit the regulatable means to act.

4. In a pump of the character described, a tank having an inwardly opening check valve, a discharge pipe extending from the bottom of the tank and having a check valve, a pipe leading from a source of compressed fluid into the tank and having a valve, an exhaust pipe leading from the tank and having a valve, means positively acting to urge the first named valve to a closed position and the exhaust valve to an open position, a valve

operating element common to both of said valves and including a chamber and a piston therein, pressure means acting as the liquid rises in the tank to compress fluid on the side of said piston opposite the urging means until the pressure counterbalances the urging means to thus cause the closure of the exhaust valve and the opening of the compressed fluid inlet valve, and means for causing approximate balancing of pressures on opposite sides of the piston when the liquid has lowered in the tank to a predetermined degree to thus permit the urging means to close the compressed fluid inlet valve and open the exhaust valve.

5. In a pump of the character described, a tank having an inwardly opening check valve, intake and exhaust ports, said tank being adapted to be submerged, a discharge 20 for said tank having an outwardly opening check valve, controlling means shiftable upon unbalancing of the pressure at opposite ends thereof for controlling the inlet and exhaust ports, a source of fluid pressure supply in communication with the intake port and an adjustable weight urging the controlling means to a position where the inlet of compressed fluid is cut off and exhaust permitted, and means whereby the ingress of liquid to said tank to a predetermined degree 30 counteracts said weight to thereby cause the opening of the exhaust valve and the closing of the compressed fluid inlet valve whereby when liquid has been discharged from the tank to a predetermined degree, the pressures on the opposite sides of the controlling means will be nearly balanced to thus permit the weight to close the compressed air supply valve and open the exhaust valve.

40 6. In a pump of the character described, a tank having an inlet valve, a discharge pipe leading from the tank, a chamber having therein a piston, a piston rod extending through the chamber, a compressed fluid supply pipe having a valve, an exhaust pipe having a valve, both of said pipes being connected to the tank, the valves being connected to the piston rod for simultaneous operation in relatively reverse directions, a lever engaged with the piston rod and carrying a weight urging the piston rod in a direction to close the supply valve and open the exhaust valve, means for transmitting a greater fluid pressure to the interior of the chamber on that side of the piston opposite the lever than is transmitted to the other side of the piston to thereby counter-balance said weight and open the supply valve while closing the exhaust valve when the tank is filled to a predetermined degree and reducing the fluid pressure against said face of the piston relative to the fluid pressure on the opposite face when the tank has emptied to a predetermined degree to thereby permit the weight to close the supply valve and open the exhaust valve.

7. In a pump of the character described, a tank having an inlet valve, a discharge pipe leading from the tank, a chamber having therein a piston, a piston rod extending through the chamber, a compressed fluid supply pipe having a valve, an exhaust pipe having a valve, both of said pipes being connected to the tank, the valves being connected to the piston rod for simultaneous operation in relatively reverse directions, a lever engaged with the piston rod and carrying a weight urging the piston rod in a direction to close the supply valve and open the exhaust valve, means for transmitting fluid pressure from within the tank to both sides of the piston, said means causing a greater pressure upon that side of the piston opposite the lever than to the other side of the piston when the tank is filled to a predetermined degree to thus counter-balance said weight and open the supply valve while closing the exhaust valve.

8. In a pump of the character described, a tank having an inlet valve, a discharge pipe leading from the tank, a chamber having therein a piston, a piston rod extending through the chamber, a compressed fluid supply pipe having a valve, an exhaust pipe having a valve, both of said pipes being connected to the tank, the valves being connected to the piston rod for simultaneous operation in relatively reverse directions, a lever engaged with the piston rod and carrying a weight urging the piston rod in a direction to close the supply valve and open the exhaust valve, means for transmitting fluid pressure from within the tank to both sides of the piston, said means causing a greater pressure upon that side of the piston opposite the lever than to the other side of the piston when the tank is filled to a predetermined degree to thus counter-balance said weight and open the supply valve while closing the exhaust valve, means for transmitting fluid pressure from within the tank to both sides of the piston, said means causing a greater pressure upon that side of the piston opposite the lever than to the other side of the piston when the tank is filled to a predetermined degree to thus counter-balance said weight and open the supply valve while closing the exhaust valve, and comprising a balance pipe extending from that end of the chamber opposite the lever down into the tank to a point adjacent to or above the lower end of the discharge pipe and an equalizer pipe extending from the top of the tank into the opposite end of the chamber.

9. In a pump of the character described, a tank having an inlet valve, a discharge valve leading from the tank, a chamber having therein a piston, a piston rod extending through the chamber, a compressed fluid supply pipe having a valve, an exhaust pipe having a valve, both of said pipes being connected to the tank, the valves being connected to the piston rod for simultaneous operation in relatively reverse directions, a lever engaged with the piston rod and carrying a weight urging the piston rod in a direction to close the supply valve and open the exhaust valve, a balance pipe extending from that end of the chamber opposite the

lever down into the tank to a point adjacent to but above the lower end of the discharge pipe and having a downwardly opening bell larger in diameter than the balance pipe and an equalizer pipe extending from the tank and opening into that end of the chamber adjacent the lever.

10. In a pump of the character described, a tank having an inlet valve, a discharge valve leading from the tank, a chamber having therein a piston, a piston rod extending through the chamber, a compressed fluid supply pipe having a valve, an exhaust pipe having a valve, both of said pipes being connected to the tank, the valves being connected to the piston rod for simultaneous operation in relatively reverse directions, a lever engaged with the piston and carrying a weight urging the piston rod in a direction to close the supply valve and open the exhaust valve, a balance pipe extending from that end of the chamber opposite the lever down into the tank to a point adjacent to but above the lower end of the discharge pipe and having a downwardly opening bell larger in diameter than the balance pipe and an equalizer pipe extending from the tank and opening into that end of the chamber adjacent the lever, the lever having a movable weight shiftable as the lever is tilted from a horizontal position from one end of the lever to the other.

11. In a pump of the character described, a tank having a discharge pipe, a compressed fluid supply pipe having a valve, an exhaust pipe having a valve, both of said pipes being connected to the tank, a piston, a piston rod extending through the chamber, the valves being connected to the piston rod for simultaneous operation in relatively reverse directions, a chamber having therein a piston carrying said rod, a balance pipe extending down into the tank to a point adjacent to but above the lower end of the supply pipe, and connected to said chamber on one side of the piston, an equalizer pipe connected to the chamber on the opposite side of the piston, and means whereby absorption of compressed fluid in the balance pipe may be compensated for.

12. In a pump of the character described, a tank having an inlet valve and a discharge pipe, a chamber having therein a piston, a piston rod extending through the chamber, a compressed fluid supply pipe having a valve and extending down into the tank and terminating in a downwardly opening bell adjacent to but above the lower end of the discharge pipe, an exhaust pipe leading from the upper end of the tank and having a valve, said piston rods being connected to the valves to operate them in relatively reverse directions, means urging the piston rod in a direction to close the supply valve and open the exhaust valve, a connection from the air supply pipe between its valve and the tank

to that end of the chamber opposite the urging means, and a connection from the exhaust pipe to the opposite end of the chamber.

13. In a pump of the character described, a tank having an inlet valve and a discharge pipe, a chamber having therein a piston, a piston rod extending through the chamber, a compressed fluid supply pipe having a valve and extending down into the tank and terminating in a downwardly opening bell adjacent to but above the lower end of the discharge pipe, an exhaust pipe leading from the upper end of the tank and having a valve, said piston rod being connected to the valves to operate them in relatively reverse directions, speed reducing valves on the inlet side of the supply pipe and outlet side of the exhaust pipe, means urging the piston rod in a direction to close the supply valve and open the exhaust valve, a connection from the air supply pipe between its valve and the tank to that end of the chamber opposite to the urging means, and a connection from the exhaust pipe to the opposite end of the chamber.

14. In a mechanism of the character described, a compressed fluid supply pipe and an exhaust pipe, valves for said pipes, pressure operated means for reversely operating said valves, means for urging said pressure operated means in a direction to close the fluid supply valve and open the exhaust valve comprising a lever tiltable in a vertical plane, and having an arm operatively engaging said means, and an arm carrying an adjustable counter-weight, the lever including a tubular element extending longitudinally thereof and having therein material freely movable as the lever is tilted from one end to the other of the tubular element whereby to retard the movement of the lever toward the horizontal position and accelerate the movement of the lever after it has passed its horizontal position.

15. In a mechanism of the character described, a tank having an inlet valve and a discharge pipe extending from near the bottom of the tank, a chamber having therein a piston and a piston rod, a balance pipe extending from a point within the tank above the lower end of the discharge pipe and communicating with the interior of said chamber on one side of the piston, an equalizer pipe communicating between the other side of the chamber and the top of the tank, means for introducing compressed air into the interior of the chamber at the top thereof or exhausting air therefrom, and including reversely operated valves, a piston rod being operatively connected to said valves to reversely operate them when the piston is moved from a normal position in either direction, a lever pivoted intermediate its ends and having one arm engaged with the piston rod, a permanent weight urging the other

arm downward to thereby shift the piston rod to a position to close the compressed air supply valve and open the exhaust valve, the lever having a movable weight shiftable from one end of the lever to the other.

5 In testimony whereof I hereunto affix my signature.

WALTER S. HULSE.
